UNITED STATES PATENT OFFICE.

LÉON SAIVES, OF BILLANCOURT, FRANCE, ASSIGNOR TO LOUIS RENAULT, OF BILLANCOURT, FRANCE.

METALLIC FLOORING PLATE FOR SHOPS AND LIKE USES.

Application filed February 4, 1928, Serial No. 251,984 and in France November 10, 1927.

The present invention relates to a new construction for metallic flooring plates, which is chiefly adapted for the flooring of factories. The said flooring plates are 5 adapted to form a flooring whose parts are connected together in such manner that the flooring will not suffer deformation under the simultaneous action of the weight of heavy machine pieces, and of the heating to 10 which the said flooring may be subjected in certain cases.

The rigidity of flooring plates and of their connecting members is very simply obtained by the treatment of the steel plate of the 15 proper thickness by the stamping or pressing process, and this operation will simultaneously produce the stiffening ribs or corrugations on the plates as well as the portions for attaching the auxiliary assembling pieces.

20 The said flooring is constructed according to the principle of ceramic tiling with octagonal tiles and small filling plates, but in my said device the filling part consists of two concave pieces fitted together, whereof one 25 is placed at the upper part and the other at the lower part of the flooring plate, said concave pieces being in contact at their edges with the cut-off corners of the four plates which coincide at a given place. The whole 30 device is held in place by a suitable bolt.

The appended drawings show by way of example an embodiment of the invention.

Fig. 1 is plan view of a flooring plate, showing also the commencement of the three 35 adjacent plates, and the assembling arrangement for the said flooring plates. Fig. 2 is a section on the line A—A of Fig. 1. Fig. 3 is a sectional view showing the cut-off corners. Fig. 4 is a sectional view of the assembled device on the line B—B of Fig. 1.

40 Each of the flooring plates consists of a square sheet metal plate 1, which is pressed into the form of an inverted concave piece. In the pressing process, there are formed a certain number of stiffening ribs or corrugations 2 of suitable form, and the four corners are also cut off, as shown in Fig. 3 so 45 as to substitute for the square, an octagon comprising four small sides 3. The drawings also show, upon the part connecting the upper face and the small side 3, an additional recess 4.

The square space which is thus formed between the four plates meeting at a given 50 angle, is adapted to receive the device con-

sisting of two pressed sheet metal concave members 5 and 6. One of the said members 5 fits into the said space, since its flanged edges coact with the edges of the recess 4. The second concave member 6 is disposed 60 upon the lower face of the plate, and it fits upon the outside of the small sides 3. The members 5 and 6 are pierced with central holes for the insertion of the assembling bolt 8. When drilling the concave member 6, there are detached and turned down two or 65 four tongues 9, between which is held the bolt head 10, thus preventing it from turning, so that the nut 11 may be turned to hold the device together.

70 The flooring which is thus formed may undergo slight deformations, but without any prejudice to its continuity. It can be very simply manufactured, since all the pieces are obtained from sheet metal by the 75 pressing process. A sufficient space is allowed between the several plates in order to permit the expansion of the pieces at high temperatures.

80 Obviously, the details of construction herein described are given solely by way of example, and they may be varied without departing from the principle of the invention, this consisting essentially in the use of octagonal facing plates consisting of pressed sheet metal, the four sides of the square space formed at each corner of the plate being held 85 between two pressed metal concave members of suitable shape, with the use of a clamping device.

90 The use of the said flooring plates is not limited to foundries or machine shops, but such plates can be used in general building construction.

95 While it is true that the pressing process as applied to metal plates is the most reliable and economical for the manufacture of all the pieces of the flooring, other means may be employed for the manufacture of the auxiliary members such as the concave connecting members.

Claims:

1. In a metallic flooring for factories, pressed metal plates of square form provided with four small sides at the corners completing an octagonal form, a downward flange on the edges of the metal plates and recesses on the surface of the plates in front of the small sides, an upper concave member of square form fitting into the recesses of

105

110

four adjacent plates, an under concave member underneath engaging the flanges of the same adjacent plates, and means for clamping together the two concave members.

5 2. In a metallic flooring for factories as claimed in claim 1, pressed metal plates of square form provided with four small sides at the corners completing an octagonal form, a downward flange on the edges of the metal

10 plates and recesses on the surface of the plates in front of the small sides, an upper

concave member of square form fitting into the recesses of four adjacent plates, an under concave member underneath engaging the flanges of the same adjacent plates, down turned tongues centrally provided in the under concave member, and a bolt device clamping together the two concave members the head of which is inserted between the downturned tongues.
